[57] CLAIM

The ornamental design for a receptacle for electronic bar code reader, as shown and described.

DESCRIPTION

FIG. 1 is a top, bottom end, right side perspective view of a receptacle for electronic bar code reader showing our new design;

FIG. 2 is a top plan view thereof;

FIG. 3 is a left side elevational view thereof;

FIG. 4 is a right side elevational view thereof;

FIG. 5 is a top end elevational view thereof;

FIG. 6 is a bottom end elevational view thereof;

FIG. 7 is a perspective view thereof with an electronic bar code reader being shown in broken lines for illustrative purposes only and forms no part of the claimed design;

FIG. 8 is a top, bottom end, right side perspective view of a second embodiment of our design;

FIG. 9 is a top plan view thereof;

FIG. 10 is a left side elevational view thereof;

FIG. 11 is a right side elevational view thereof;

FIG. 12 is a top end elevational view thereof;

FIG. 13 is a bottom end elevational view thereof;

FIG. 14 is a perspective view thereof with an electronic bar code reader being shown in broken lines for illustrative purposes only and forms no part of the claimed design;

FIG. 15 is a top, bottom end, right side perspective view of a third embodiment of our design;

FIG. 16 is a top plan view thereof;

FIG. 17 is a top end elevational view thereof;

FIG. 18 is a left side elevational view thereof, the right side elevational view being a mirror image;

FIG. 19 is a perspective view thereof, with an electronic bar code reader being shown in broken lines for illustrative purposes only and forms no part of the claimed design.

The rear of each embodiment is flat and unornamented.

FIG. 1.FIG. 2.FIG. 5.FIG. 3.FIG. 4.FIG. 6.FIG. 7.
